CHAFE-IRON.

No. 838,883.

Specification of Letters Patent.

Patented Dec. 18, 1906.

Application filed February 27, 1906. Serial No. 303,185.

To all whom it may concern:

Be it known that I, CALEB T. McCLELLAND, a citizen of the United States, and a resident of Olympia, in the county of Thurston and State of Washington, have invented an Improved Rub-Iron, of which the following is a specification.

My invention is an improvement in devices termed "rub-irons" or "chafe-irons," which are applied to the sides of wagon beds or bodies for protecting them from wear and defacement by contact with the forward wheels in making sharp turns. I have devised an improved construction of such devices, the same being composed of two parts, one being adapted to be secured to the wagon-body and to hold the other, which is the wear-piece proper, in such manner that it may be removed when worn out and a new one substituted with convenience and despatch.

The details of construction, arrangement, and combination of parts are as hereinafter described, reference being had to the accompanying drawings, in which—

Figure 1 is a perspective view illustrating the application of my improved rub-iron to a wagon-body. Fig. 2 is a central vertical transverse section of the parts shown in Fig. 1. Figs. 3 and 4 illustrate in perspective the two parts of the rub-iron separated from each other.

A and B indicate the two parts of my improved rub-iron. The main part A, in which the removable wear-piece B is held when in use, is a thick flat plate having the central portion of one side cut out at x (see Fig. 3) to receive part B, and the remaining portion of such side provided with a vertical flange a. This part A is applied to the lower side edge of a wagon-body y, as shown in Figs. 1 and 2, the flange a abutting the outer side and the wagon-body and the horizontal part the under side of the body, as shown. The means for securing the plate A are screw-bolts c, which pass through its ends and the foot of the wagon-bed, as shown in Fig. 2. The wear-piece B has a flat horizontal portion and a flange b, corresponding to the plate A, and its ends b' are so formed on converging lines that it constitutes a dovetail adapted to fit in the corresponding notch or

recess x in plate A. It is apparent that by this relative construction of the parts A B the latter is held from disengagement laterally or in a horizontal direction. For supporting the part B vertically or in the same horizontal plane with plate A the contacting end edges a' b' of the two parts are inclined from the lower edge outward—that is to say, the end edges a' of the notched portion of the plate A are beveled outward from the lower side of said plate, and the adjacent edges b' of part B are similarly inclined from its lower side outward. The two parts are thus held together when applied to a wagon-body y, as shown, yet the wear-piece B may be separated from plate A by lifting it vertically when the latter is detached from the wagon-body. By this simple and inexpensive construction and combination of parts I produce a rub-iron whose wear-piece proper may be easily removed and a new one substituted therefor when required, while the larger or main part of the same may be used indefinitely. In other words, by renewal of the small wear-piece B when worn out and substituting a new one I practically renew the rub-iron entirely and at less than half the cost of the whole device. In practice two or more wear-pieces B may be kept in stock and sold along with each main part A by manufacturers or dealers in this class of carriage-irons.

What I claim is—

1. The improved rub-iron composed of two separable parts each having a flat body portion and a vertical flange on one side, and the larger part or plate having in its inner side a dovetail notch in which the other part is adapted to fit, their contacted end edges being inclined horizontally and vertically so that when in use the central wear-piece is supported and held from detachment in both directions, substantially as described.

2. The improved rub-iron composed of a main part having an upwardly-projecting side flange and a dovetail notch in the same side, and a piece having a dovetail shape similar to said notch and thus adapted to fit and be held in the same, substantially as shown and described.

3. The improved rub-iron composed of a main part having in one side a dovetail notch

and a wear-piece having a shape and size corresponding to said notch, whereby when the device is in use the wear-piece is held from detachment downward or horizontally, substantially as shown and described.

4. The improved rub-iron composed of two separable parts each having a flat body portion and one provided with a notch in which the other is adapted to fit, the contacting edges of the two parts being so constructed that the inserted piece is supported vertically and horizontally, substantially as described.

5. The combination with a wagon-bed of the rub-iron composed of a main plate having a dovetail notch in its outer side, and a wear-piece proper shaped corresponding to said notch and adapted to fit therein, and

means for securing the main plate to the wagon-bed, substantially as described. ²⁰

6. The combination, with a wagon-body of the rub-iron composed of a main part, or plate, having an upwardly-projecting flange on one edge and a dovetail notch in said edge, and a wear-piece consisting of a plate having ²⁵ an upturned flange at its outer edge and its body portion being shaped corresponding to the notch in the main plate, whereby, when, in normal position, it is supported and held, and means for securing the main plate to the ³⁰ wagon-body, substantially as described.

CALEB T. McCLELLAND.
